Primary Examiner — Daniel J Domino*Assistant Examiner* — Samina Vieth(74) *Attorney, Agent, or Firm* — Leason Ellis LLP(57) **CLAIM**

The ornamental design for a touch screen, as shown and described.

DESCRIPTION

FIG. 1 is a front-perspective view according to a First Embodiment of our design;

FIG. 2 is a rear-perspective view thereof;

FIG. 3 is a front view thereof;

FIG. 4 is a rear view thereof;

FIG. 5 is a left-side view thereof;

FIG. 6 is a right-side view thereof;

FIG. 7 is a top plan view thereof;

FIG. 8 is a bottom plan view thereof;

FIG. 9 is a front-perspective view according to a Second Embodiment of our design;

FIG. 10 is a rear-perspective view thereof;

FIG. 11 is a front view thereof;

FIG. 12 is a rear view thereof;

FIG. 13 is a left-side view thereof;

FIG. 14 is a right-side view thereof;

FIG. 15 is a top plan view thereof;

FIG. 16 is a bottom plan view thereof;

FIG. 17 is a front-perspective view according to a Third Embodiment of our design;

(Continued)

FIG. 18 is a rear-perspective view thereof;
 FIG. 19 is a front view thereof;
 FIG. 20 is a rear view thereof;
 FIG. 21 is a left-side view thereof;
 FIG. 22 is a right-side view thereof;
 FIG. 23 is a top plan view thereof;
 FIG. 24 is a bottom plan view thereof;
 FIG. 25 is a front-perspective view according to a Fourth Embodiment of our design;
 FIG. 26 is a rear-perspective view thereof;
 FIG. 27 is a front view thereof;
 FIG. 28 is a rear view thereof;
 FIG. 29 is a left-side view thereof;
 FIG. 30 is a right-side view thereof;
 FIG. 31 is a top plan view thereof; and,
 FIG. 32 is a bottom plan view thereof.
 Conventional shading is illustrated for purposes of highlighting the line drawings, but forms no part of the claimed design.
 The broken lines showing of portions of the touch screen article form no part of the claimed design.

1 Claim, 32 Drawing Sheets
